UNITED STATES PATENT OFFICE.

JOHN A. BACHMAN, OF PHILADELPHIA, PENNSYLVANIA.

DESIGN FOR A CONFECTION.

45,285.

Specification for Design.

Patented Feb. 24, 1914.

Application filed December 31, 1913. Serial No. 809,759. Term of patent 7 years.

To all whom it may concern:

Be it known that I, JOHN A. BACHMAN, a citizen of the United States, residing at Philadelphia, in the county of Philadelphia and State of Pennsylvania, have invented a new, original, and ornamental Design for a Confection, of which the following is a specification, reference being had to the accompanying drawing, forming part hereof.

The figure is a plan view of a confection showing my new design.

I claim:

The ornamental design for a confection as shown.

JOHN A. BACHMAN.

Witnesses:

WILLIAM J. BURNS,

VICTOR PAUL.
